UNITED STATES PATENT OFFICE.

STEPHAN BROICHGANS, OF MILWAUKEE, WISCONSIN, ASSIGNOR TO THE
PERFECT GAS MACHINE COMPANY, OF MILWAUKEE, WISCONSIN, A
CORPORATION OF WISCONSIN.

GAS AND AIR MIXER.

SPECIFICATION forming part of Letters Patent No. 708,308, dated September 2, 1902.

Application filed December 30, 1901. Serial No. 87,784. (No model.)

To all whom it may concern:

Be it known that I, STEPHAN BROICHGANS, residing at Milwaukee, in the county of Milwaukee and State of Wisconsin, have invented 5 a new and useful Improvement in Air and Gas Mixers, of which the following is a description, reference being had to the accompanying drawings, which are a part of this specification.

10 My invention has relation to improvements in air and gas mixers of that class in which air is mixed with gas or with vapor from gasoline or other volatile substances for light and fuel.

15 In devices of the above character it is the aim to mix the vapors of gasoline or other volatile substances with air in proper proportion in order to produce a uniform gas of unvarying candle-power. In devices as heretofore constructed a weight-balanced float 20 has been provided arranged within a mixing-chamber with an air-valve so attached to or with such float that the motions of the float and attached valve are identical, the movement 25 of the valve being limited to the movement of the float. In this form of devices a lever has been used as a means of suspending and balancing the float, the said float being attached to one end of the lever and a counter- 30 balancing-weight at the other end, the sole and essential function of said lever being to suspend and balance said float. In such devices the movement of the valve is accomplished solely and directly by the float with- 35 out the intervention of the lever and is in no sense dependent upon the operation of the lever.

It is the primary object of my invention to provide a form of construction wherein the 40 opening and closing of the valve for regulating the admission of air is accomplished by a mechanism which includes a lever, said mechanism being separate and distinct from the float, but operated by the float, the movement 45 of the valve being directly dependent upon the movement of the pivoted lever, the suspension and balancing of said float being entirely independent of said lever.

50 A further object resides in the provision of an improved form of sustaining device to counteract the weight of the material of

which the float is constructed, whereby the float becomes more sensitive to the changing condition of the vapor within the mixing-chamber when the air is mixing with the gas, 55 thus accomplishing an accurate mixture of gas and air and avoiding an accumulation of too heavy or too thin a vapor. The means of suspension of the float also permits an adjustment of the float while the apparatus is in actual 60 operation without permitting the escape of a dangerous quantity of gas, thus allowing for a more accurate adjustment than with present devices.

With the above and other incidental objects in view the invention consists of the devices and parts or their equivalents, as hereinafter set forth.

In the accompanying drawings, Figure 1 is a vertical sectional view of my invention, and Fig. 2 is a horizontal section on the line 2 2 of Fig. 1.

Referring to the drawings, the numeral 3 indicates an outer casing of any desirable shape and forming an interior mixing-chamber 4. Within the chamber is a float 5 of the ordinary and usual form of construction employed in devices of this character. Extending from the float is a rod 6. This rod extends through the end of the casing, preferably into a tube 7, projecting outwardly from said end of the casing. The portion of the rod within the tube is surrounded by a coiled spring 8, which spring is confined between the end of the casing and nuts 9 9, 85 turned onto the threaded extremity of the rod. The outer end of the tube is provided with a threaded cap 10, which when removed affords opportunity to gain access to the interior of the tube for the purpose of turning 90 the nuts and adjusting the tension of the spring. While the rod 6 could project directly from the end of the float, yet I prefer to extend said rod through the float and beyond the same for a desired distance and 95 freely through an opening in a cross-bar 11, disposed beneath one end of the float. By this arrangement a means is provided for accurately guiding the float and rod in their vertical movement. Leading to the casing, 100 preferably to the bottom thereof, and communicating with the interior mixing-chamber

of said casing is the air-inlet pipe 12, through which the air is supplied at the proper pressure. Also leading from a carburetor or other source of supply (not shown) to the casing 5 and communicating with the interior chamber of said casing is the gas-inlet pipe 13, and leading from the casing is the mixed air and gas eduction pipe 14, which extends to the burners or other medium to be supplied with 10 the gas.

Within the mixing-chamber 4 is a lever 15, which at one end is pivoted to the wall of the casing and at its opposite or free end has suspended therefrom a chain or other suitable 15 device 16, said chain or device carrying at its lower end a valve 17, which is seated on a valve-seat 18 in the air-inlet pipe 12. A suitable connection should be provided between the rod 6 and an intermediate portion of the 20 lever, so as to cause said lever to be turned on its pivot or fulcrum on the rising and falling of the float. I prefer that this connection should be a pivotal connection, and a 25 convenient arrangement for this purpose is shown in the accompanying drawings, wherein the rod is illustrated as provided with a collar 19, said collar having pivots or pintles 20 20, projecting from diametrically opposite points thereof and pivotally engaging the 30 side pieces of a yoke-like intermediate portion 21 of the lever.

Referring to the operation of the invention, the tension of the spring 8 is first regulated so that when vapor of the desired richness is 35 passing into the chamber 4 and out of said chamber to the burners the action of said gas upon the float will not be sufficient to raise said float against the gravity of the float. As the float under these conditions remains at a 40 state of rest, it is of course obvious that the lever 15 is not turned, and hence the valve 17 remains closed. As soon, however, as the vapor-current becomes too rich or too highly charged or saturated the resulting increase 45 of its density will cause the float to rise, and this rising of the float causes the lever to be turned in a direction to raise the valve 17, and thereby admit a quantity of air into the mixing-chamber sufficient to restore the gas 50 to its proper condition of density. When gas is being drawn from the mixing-chamber, the float through the described operation of course varies the position of the valve 17 in accordance with the amount of air required 55 from time to time to keep the gas in the mixing-chamber in proper condition.

From the foregoing description it will be seen that I provide a simple device or apparatus for the purpose and one at the same 60 time which possesses the advantage of having the operation of the valve which controls the admission of air directly and solely dependent upon the actuation of the lever. Attention is also directed to the fact that by utilizing the lever as I do in my invention a greater control of the valve is obtained than when the valve is connected directly to the float—

that is to say, the construction provides for the opening of the valve more quickly—and hence providing for a quick entrance of the air into 70 the mixing-chamber, and also provides for the closing of the valve quickly to shut off the entrance of the air instantly. By this arrangement a more uniform gas is provided by reason of the better control of the valve, 75 and in this construction also it is not necessary that the float move to a considerable extent in order to admit the proper quantity of air. By the employment also of my improved form of sustaining device to counteract the 80 weight of the material of which the float is constructed the said float becomes more sensitive to the changing condition of the vapor within the mixing-chamber when the air is mixing with the gas, thus accomplishing an 85 accurate mixture of gas and air and avoiding an accumulation of too heavy or too thin a vapor. Also by reason of the fact that the tension of the spring may be regulated an adjustment of the float is made possible while 90 the apparatus is in actual operation without permitting the escape of a dangerous quantity of gas, thus allowing for a more accurate adjustment than with present devices. All that is necessary to be done in order to effect 95 this adjustment when the apparatus is in actual operation is merely to remove the cap 10 and then turn the nuts 9.

What I claim as my invention is—

1. The combination of a mixing-chamber 100 having a gas-inlet port, a mixed air and gas eduction port, and an air-inlet port, the latter adapted to deliver air to said mixing-chamber, a float within the chamber, means for suspending the float, a pivoted lever within 105 the mixing-chamber, a connection between the float and the lever, whereby said lever is turned on its fulcrum when the float is moved, a valve for controlling the air-inlet port, and a connection between the valve and the lever, 110 whereby the movement of the lever causes the valve to be moved away from or toward its seat.

2. The combination of a mixing-chamber having a gas-inlet port, a mixed air and gas 115 eduction port, and an air-inlet port, the latter adapted to deliver air to said mixing-chamber, a float within the chamber, elastic means for suspending the float, a pivoted lever within 120 the chamber, a connection between the lever and the float, whereby said lever is turned on its fulcrum when the float is moved, a valve for controlling the air-inlet port, and a connection between the valve and the lever, 125 whereby the movement of the lever causes the valve to be moved away from or toward its seat.

3. The combination of a mixing-chamber having a gas-inlet port, a mixed air and gas eduction port, and an air-inlet port, the latter adapted to deliver air to said mixing-chamber, a float within the chamber, an adjustable 130 means for suspending the float, a pivoted lever within the chamber, a connection be-

- 5 between the lever and the float, whereby said lever is turned on its fulcrum when the float is moved, a valve for controlling the air-inlet port, and a connection between the valve and the lever, whereby the movement of the lever causes the valve to be moved away from or toward its seat.
4. The combination of a mixing-chamber having a gas-inlet port, a mixed air and gas reduction port, and an air-inlet port, the latter adapted to deliver air to said mixing-chamber, a float within the chamber, means for suspending the float, a rod extending from the float, a pivoted lever within the chamber and adapted to be actuated by the rod, when the float is moved, a valve for controlling the air-inlet port, and a connection between the valve and the lever whereby the movement of the lever causes the valve to be moved away from or toward its seat.
5. The combination of a mixing-chamber having a gas-inlet port, a mixed air and gas reduction port, and an air-inlet port, the latter adapted to deliver air to said mixing-chamber, a float within the chamber, means for suspending said float, a rod extending from the float, a pivoted lever within the chamber and having a pivotal connection with the rod, whereby said lever is actuated when the float is moved, a valve for controlling the air-inlet port, and a connection between the valve and the lever, whereby the movement of the lever causes the valve to be moved away from or toward its seat.
- 35 6. The combination of a mixing-chamber having a gas-inlet port, a mixed air and gas reduction port, and an air-inlet port, the latter adapted to deliver air to said mixing-chamber, a float within the chamber, a rod extending from the float, a pivoted lever within the chamber and adapted to be actuated by the rod when the float is moved, a valve for controlling the air-inlet port, a connection between the valve and the lever, whereby the movement of the lever causes the valve to be moved away from or toward its seat, and a coiled spring surrounding the rod and confined between a fixed part and an enlargement on the rod, said spring adapted to yieldingly suspend the float.
7. The combination of a mixing-chamber having a gas-inlet port, a mixed air and gas reduction port, and an air-inlet port, the latter adapted to deliver air to said mixing-chamber, a float within the chamber, a rod extending from the float, a coiled spring surrounding the rod and confined between a fixed part and an enlargement on the rod, said spring adapted to suspend the float, a valve for controlling the air-inlet port, and means adapted as the float rises or falls for causing the valve to be moved away from or toward its seat.
8. The combination of a mixing-chamber having a gas-inlet port, a mixed air and gas reduction port, and an air-inlet port, the latter adapted to deliver air to said mixing-chamber, a float within the chamber, a rod extending from the float, a coiled spring surrounding the rod and confined between a fixed part and an enlargement on the rod, said spring adapted to suspend the float, a valve for controlling the air-inlet port, means for regulating the tension of the spring, and means adapted as the float rises or falls for causing the valve to be moved away from or toward its seat.
- 15 9. The combination of a mixing-chamber having a gas-inlet port, a mixed air and gas reduction port, and an air-inlet port, the latter adapted to deliver air to said mixing-chamber, a tube extending from the end of the mixing-chamber, a float within the chamber, a rod extending from the float and through the end of the mixing-chamber and into the tube, a coiled spring within the tube and surrounding the rod and confined between a fixed part, and an enlargement on the rod, said spring adapted to suspend the float, a valve for controlling the air-inlet port, and means adapted as the float rises or falls for causing the valve to be moved away from or toward its seat.
- 20 10. The combination of a mixing-chamber having a gas-inlet port, a mixed air and gas reduction port, and an air-inlet port, the latter adapted to deliver air to said mixing-chamber, a float within the chamber, means for suspending the float, a valve for controlling the air-inlet port, means adapted as the float rises or falls for causing the valve to be moved away from or toward its seat, and means for guiding the float in its movement.
- 25 11. The combination of a mixing-chamber having a gas-inlet port, a mixed air and gas reduction port, and an air-inlet port, the latter adapted to deliver air to said mixing-chamber, a float within the chamber, means for suspending the float, a valve for controlling the air-inlet port, means adapted as the float rises or falls for causing the valve to be moved away from or toward its seat, a rod extending from the float, and a device which the rod engages, said device adapted for guiding the float in its movement.
- 30 12. The combination of a mixing-chamber having a gas-inlet port, a mixed air and gas reduction port, and an air-inlet port, the latter adapted to deliver air to said mixing-chamber, a float within the chamber, means for suspending the float, a valve for controlling the air-inlet port, means adapted as the float rises or falls for causing the valve to be moved away from or toward its seat, a rod extending from the float, and a guide-bar having an opening through which the rod passes, whereby the float is guided in its movement.
- 35 In testimony whereof I affix my signature in presence of two witnesses.

STEPHAN BROICHGANS.
